LIQUEFACTION OF NITROGEN IN REGASIFICATION OF LIQUID METHANE

Hadi Hashemi-Tafteshi, London, England, assignor to Conch International Methane Limited, Nassau, Bahamas, a corporation of Bahamas

Filed June 16, 1960, Ser. No. 36,643

13 Claims. (Cl. 62—9)

This invention relates to producing liquid nitrogen in the course of the regasification of liquid methane. The liquid methane may come from any source and in particular may be liquefied natural gas which consists primarily of methane. In this specification, therefore, references to methane mean pure methane or any gas mixture, the major ingredient of which is methane.

The invention provides a method of producing liquid nitrogen in the course of the regasification of liquid methane which comprises

(a) Cooling gaseous nitrogen by indirect heat exchange with compressed liquid methane to produce compressed gaseous methane,

(b) Comprising the cold gaseous nitrogen from step (a),

(c) Condensing the cold compressed gaseous nitrogen from step (b) by indirect heat exchange with liquid methane to produce compressed liquid nitrogen and gaseous methane, and

(d) Heating the compressed gaseous methane from step (a) and expanding it to produce energy.

The energy produced in step (d) of the above method (which method is hereinafter sometimes called "Method A") may be used to drive the compressors used in the process so that the only external source of power is the heat put into the system in step (d). This may be provided very cheaply from waste hot water. The whole of the refrigeration necessary to produce the liquid nitrogen in this method may be obtained from liquid methane so that no other source of refrigeration is required. The compression power required in the method is reduced to a minimum by ensuring that the inlet temperatures to the various compressors are as low as possible and in any case not higher than about -200° F.

It will be appreciated that the various temperatures and pressures employed in the method of the invention will be inter-related. Typical temperature and pressures are given in the more detailed description hereinafter appearing. However, generally the nitrogen will be cooled to -200° F. to -250° F. in step (a).

The gaseous nitrogen used as a feed in Method A may come from any suitable source; for example, it may be a by-product from a separate air rectification plant. Preferably, however, it comes from an air rectification plant built into, and operating in conjunction with, the liquid methane regasification plant. A suitable method for operating such a combined plant comprises

(a) Cooling compressed gaseous nitrogen taken overhead from an air rectification column by indirect heat exchange with compressed liquid methane to produce compressed gaseous methane,

(b) Further compressing the cold gaseous nitrogen from step (a),

(c) Condensing the cold compressed gaseous nitrogen from step (b) by indirect heat exchange with liquid methane to produce compressed liquid nitrogen and gaseous methane,

(d) Cooling the air stream to the air rectifier by indirect heat exchange with compressed liquid methane to produce compressed gaseous methane,

(e) Heating the compressed gaseous methane from steps (a) and (d) and expanding it to produce energy,

(f) Further cooling the cold air from step (d) by heat exchange with cold nitrogen and/or oxygen from the air rectifier and passing the further cooled air to the air rectifier from which gaseous nitrogen is taken off as an overhead stream,

(g) Reducing the pressure on the liquid nitrogen from step (c) to produce liquid nitrogen at a lower pressure and cold gaseous nitrogen, and

(h) Returning some of the liquid nitrogen from step (c) and/or (g) to the air rectifier as reflux,

The cold gaseous nitrogen from step (g) may join that coming overhead from the air rectifier and/or may be circulated through to coils of a reboiler in the air rectifier. Step (g) may be carried out in stages, for example, in two or more expansion chambers.

Again in this method (hereinafter sometimes called "Method B"), the compression power required is derived from energy from step (e) and all the refrigeration is obtained from the liquid methane so that the only external source of power required is the heat input in step (e).

It will be apparent that the method produces from liquid methane and air as starting materials gaseous methane, the product from steps (a) and (e), and liquid nitrogen, the product from step (g), the only external source of power being the heat input into step (e). The method also yields gaseous or liquid oxygen as will be described in more detail hereinafter.

If necessary, further energy can be obtained by using one or more external energy-producing cycles in heating up the compressed gaseous methane, for example as required in step (d) of Method A or in step (e) of Method B. The external energy-producing cycles are those of the type described in British patent specification 814,209 by heating up the compressed gaseous methane by means of an external energy-producing cycle in which heat is supplied to the compressed gaseous methane from a working medium of higher boiling point by heat exchange in a condenser in which the working medium is liquefied and the working medium is then brought to a higher pressure, vaporised at the higher pressure, expanded in an engine to produce energy and then recycled to the condenser.

The method of producing liquid nitrogen in the course of the regasification of liquid methane which is the subject of the invention will now be described with reference to the accompanying drawings, in which

FIGURE 1 is a flow diagram of a simple process operating in accordance with Method A, and

FIGURE 2 is a flow diagram of a process operating in accordance with Method B, and

FIGURE 3 is a flow diagram of a modification of the process illustrated in FIGURE 2.

Referring to FIGURE 1, liquefied natural gas at its boiling point at atmospheric pressure, viz. -258° F., enters the system by a conduit 1 and is divided into two streams, one going through conduit 2 and the other through conduit 3. The stream passing through conduit 2 is compressed in compressor 4 to 1500 p.s.i.a. Its temperature will then be about -248° F. This compressed liquefied natural gas is then used to cool compressed gaseous nitrogen in heat exchangers 5 and 6. A further part of the compressed liquid natural gas is used to cool the nitrogen down to -240° F. before it is compressed. This is done in heat exchanger 7. The three streams of natural gas which have passed through the heat exchangers 5, 6 and 7 meet in conduit 8 and pass through a heat exchanger 9 where they are further warmed to 100° F. and the resulting natural gas which is still at 1500 p.s.i.a. is expanded in expander 10 down to a pressure of 390 p.s.i.a. with the production of energy. The natural gas then passes through a further heat exchanger 11 in which its temperature is raised to 100° F. It is then

passed through a further expander 12 in which its pressure is reduced to 115 p.s.i.a. and its temperature to substantially ambient with the production of energy. The effluent from expander 12 is suitable for feeding into a gas pipeline.

The source of heat in heat exchangers 9 and 11 may be a waste hot water supply or may be derived from an external energy-producing cycle of the previously described type for example a propane cycle.

The stream of liquefied natural gas passing through conduit 3 is evaporated in heat exchanger 13 in liquefying compressed nitrogen. The natural gas at atmospheric pressure may be pumped up to pipeline pressure of 115 p.s.i.a. and joined with the effluent from expander 12 if so desired.

The nitrogen stream at atmospheric pressure enters the system via conduit 14 and is cooled in heat exchanger 7 to -240° F. It is compressed in compressor 15 to 82 p.s.i.a. and again cooled to -240° F. in heat exchanger 6. It is then compressed to 300 p.s.i.a. in compressor 16 and again cooled to -240° F. in heat exchanger 5. It then passes through heat exchanger 13 in which it is liquefied to produce liquid nitrogen at -250° F. and under a pressure of 300 p.s.i.a. If the liquid nitrogen is required at atmospheric pressure, it can be fed into one or more expansion chambers to let the pressure down, the resulting cold gaseous nitrogen which flashes off being fed back into the system, if desired.

The power required in compressors 4, 15 and 16 can be derived from expanders 10 and 12 augmented if necessary by energy produced in external energy-producing cycles attached to heat exchangers 9 and 11. Similarly, energy required for pumping up gaseous methane at atmospheric pressure from the effluent of conduit 3 to a pipeline pressure of 115 p.s.i.a. may also be derived from these energy-producing sources within the cycle.

It will be appreciated that the process described in FIGURE 1 requires a source of nitrogen and that the most convenient source of nitrogen is an air rectifier. It is possible to so design the air rectification process that it can be fitted into the process of FIGURE 1 and operated without any external power apart from waste heat or refrigeration other than that provided by the liquefied natural gas. Such a process will now be described with reference to FIGURE 2.

Liquid methane at -258° F. and atmospheric pressure enters the system via conduit 20 and is divided into two streams. One of these streams in conduit 21 is compressed in compressor 22 to 1500 p.s.i.a. and the compressed methane is again divided into two streams, one of which passes through conduit 23 and the other through conduit 24. That passing through conduit 23 is used to cool, in heat exchanger 24, the incoming air stream to the air rectifier, in the course of which operation its temperature is raised to 40° F. and it is gasified. The compressed liquid methane in conduit 24 is used in heat exchanger 26 to cool compressed gaseous nitrogen, in the course of which the compressed liquid methane is gasified and its temperature raised to -100° F. The temperature of this compressed gaseous methane is raised to -50° F. in heat exchanger 27 which is the condenser of an external energy-producing cycle to be described later. Some of the compressed gaseous methane at -100° F. may be bled off before heat exchanger 27 and led to an appropriate point in heat exchanger 25 via conduit 62.

After leaving heat exchangers 25 and 27, the compressed gaseous methane streams are joined in conduit 28 and heated by means of hot water in heat exchanger 29 to 160° F. The gaseous methane at 160° F. and 1500 p.s.i.a. is expanded in expander 30 to a pressure of 400 p.s.i.a. with the production of energy. It is then heated by means of hot water in heat exchanger 31 to 160° F. 75

again and again expanded in expander 32 to a pipeline pressure of 115 p.s.i.a. with the production of energy.

The external energy-producing cycle of which heat exchanger 27 is the condenser is a closed propane cycle which operates as follows. Gaseous propane at a pressure of 15 p.s.i.a. and a temperature of -43° F. is condensed in heat exchanger 27 to liquid propane which is then compressed in compressor 34 to a pressure of 400 p.s.i.a. The compressed liquid propane coming from compressor 34 flows through a heat exchanger 35 in which it is heated by means of warm water up to 200° F. and vaporised. The warm compressed propane vapour is then expanded in expander 36 to a pressure of 15 p.s.i.a. with the production of energy. The cycle is repeated 15 continuously.

The second part of the liquid methane entering the system via conduit 20 flows through heat exchanger 37 in which it is vaporised at atmospheric pressure while cooling compressed nitrogen and liquefying it. The 20 gasified methane may be pumped up to pipeline pressure of 115 p.s.i.a. in compressor 38.

The foregoing described the flow of methane in the process in FIGURE 2. There will now be described the flow of air, oxygen and nitrogen in the process of FIGURE 2. Air at atmospheric pressure is fed through conduit 39 to compressor 40 in which it is compressed to 18 p.s.i.a. The slightly compressed air passes through heat exchanger 25 in which it is cooled from 60° F. to -240° F. by means of compressed liquid methane and cold oxygen from the air rectifier. The air then passes through a further heat exchanger 41 in which it is cooled to -290° F. by cold nitrogen and cold oxygen from the air rectifier. The air at -290° F. enters the middle of the column of the air rectifier 42. In the air rectifier 42, liquid oxygen collects at the bottom and substantially pure nitrogen goes overhead via conduit 43. The nitrogen stream in conduit 43 is at a temperature of -320° F. and a pressure of 14.7 p.s.i.a. It passes through heat exchanger 44 in which it cools liquid nitrogen returning as reflux to the air rectifier and is itself heated to -295° F. It then flows through heat exchanger 41 and then to compressor 45 in which it is compressed to 80 p.s.i.a. The compressed nitrogen then passes through heat exchanger 26 in which it is cooled to -240° F. while gasifying compressed liquid methane. The nitrogen stream at -240° F. is then compressed in compressor 46 to a pressure of 320 p.s.i.a. and is again passed through heat exchanger 26 to cool it to -240° F. The compressed gaseous nitrogen at -240° F. and 320 p.s.i.a. then passes through heat exchanger 37 in which it is liquefied in regasifying methane. Part of the liquefied nitrogen is returned to the air rectifier 42 as reflux via conduit 47, heat exchangers 41 and 44 and conduit 48. Part of it may also be fed to expansion chamber 53 via conduit 47, heat exchangers 41 and 44 and conduit 56.

Another portion of the liquefied nitrogen is fed via conduit 49 to expansion chamber 50 in which the pressure is let down to 80 p.s.i.a. resulting in a flashing off of nitrogen gas at -290° F. which is fed via conduit 51 to the coils of the reboiler 59 in the bottom of the air rectifier, in which coils it is liquefied and returned to the liquid nitrogen conduit 47 via conduit 60.

Liquid nitrogen at -290° F. collects in the bottom expansion chamber 50 and is fed from there via conduit 52 to a second expansion chamber 53 in which the pressure is let down to 15 p.s.i.a. resulting in the production of nitrogen gas at -320° F. which is taken off via conduit 54 to join the nitrogen stream from the top of the air rectifier in conduit 43. In expansion chamber 53, liquid nitrogen at -320° F. and 15 p.s.i.a. collects and is drawn off as an end product via conduit 55. Some of the liquid nitrogen from expansion chamber 50 may be led via conduit 61 back to conduit 47 and hence back to the air rectifier as reflux.

Liquid oxygen may be drawn off from the air rectifier via valve 57 but the bulk of the oxygen in this process leaves the air rectifier as a saturated vapour via conduit 58 and is used in heat exchangers 41 and 25 to cool the incoming air.

If it is desired to increase liquid oxygen production as an end product, the use of cold oxygen vapour in heat exchangers 41 and 25 can be dispensed with so that a larger proportion of liquid oxygen can be taken off via valve 57. In this case, some or all of the nitrogen will have to be bled out of the system as a gas after heat exchange in heat exchanger 25 or some external power will be required. This process is now described with reference to FIGURE 3.

Liquid methane at -258° F. and atmospheric pressure enters the system via conduit 70 and is divided into two streams. One of these streams in conduit 71 is compressed in compressor 72 to 1500 p.s.i.a. and the compressed methane is again divided into two streams, one of which passes through conduit 73 and the other through conduit 74. That passing through conduit 73 is used to cool, in heat exchanger 75, the incoming air stream to the air rectifier, in the course of which operation its temperature is raised to 40° F. and it is gasified. The compressed liquid methane in conduit 74 is used in heat exchanger 76 to cool compressed gaseous nitrogen, in the course of which the compressed liquid methane is gasified and its temperature raised to -100° F. Some of this compressed gaseous methane may be bled via conduit 77 to an appropriate point in heat exchanger 75, but the rest joins the compressed gaseous methane stream from heat exchanger 75 in conduit 78 and is then heated by means of hot water in heat exchanger 79 to 160° F. The gaseous methane at 160° F. and 1500 p.s.i.a. is expanded in expander 80 to a pressure of 400 p.s.i.a. with the production of energy. It is then heated by means of hot water in heat exchanger 81 to 160° F. again and again expanded in expander 82 to the pipeline pressure of 115 p.s.i.a. with the production of energy.

The second part of the liquid methane entering the system via conduit 70 flows through heat exchanger 87 in which it is vaporised at atmospheric pressure while cooling compressed nitrogen and liquefying it. The gasified methane may be pumped up to pipeline pressure of 115 p.s.i.a. in compressor 88.

The foregoing describes the flow of methane in the process in FIGURE 3. There will now be described the flow of air, oxygen and nitrogen in the process of FIGURE 3. Air at atmospheric pressure is fed through conduit 89 through heat exchanger 75 in which it is cooled from 60° F. to -240° F. by means of compressed liquid methane and cold nitrogen from the air rectifier. The air then passes through a further heat exchanger 91 in which it is cooled to -290° F. by further cold nitrogen from the air rectifier. The air at -290° F. enters the middle of the column of the air rectifier 92. In the air rectifier 92, liquid oxygen collects at the bottom and substantially pure nitrogen goes overhead via conduit 93. The nitrogen stream in conduit 93 is at a temperature of -320° F. and a pressure of 14.7 p.s.i.a. It passes through heat exchanger 94 in which it cools liquid nitrogen returning as reflux to the air rectifier and is itself heated to -295° F. It then flows through heat exchanger 91, after which it is divided into two streams, part passing through heat exchanger 75 and hence to atmosphere and part passing to compressor 95 in which it is compressed to 80 p.s.i.a. The compressed nitrogen then passes through heat exchanger 76 in which it is cooled to -240° F. while gasifying compressed liquid methane. The nitrogen stream at -240° F. is then divided into two streams, one of which is compressed in compressor 96 to a pressure of 320 p.s.i.a., is again passed through heat exchanger 76

to cool it to -240° F., after which it passes through heat exchanger 87 in which it is liquefied in regasifying methane. The other stream is returned to the reboiler 109 of the air rectifier 92 via conduit 97, heat exchanger 91 and conduit 110.

The nitrogen liquefied in heat exchanger 87 is fed via conduit 99 to expansion chamber 100 in which the pressure is let down to 76 p.s.i.a. resulting in a flashing off of nitrogen gas at -290° F. which is fed via conduits 101 and 110 to the coils of the reboiler 109 in the bottom of the air rectifier, in which coils it is liquefied and from which it is returned to the upper part of the air rectifier as reflux via conduits 108 and 98. Liquid nitrogen at -290° F. collects in the bottom of expansion chamber 100 and is fed from there via conduit 102 to a second expansion chamber 103 in which the pressure is let down to 15 p.s.i.a. resulting in the production of nitrogen gas at -320° F. which is taken off via conduit 104 to join the nitrogen stream from the top of the air rectifier in conduit 93. In expansion chamber 103, liquid nitrogen at -320° F. and 15 p.s.i.a. collects and is drawn off as an end product via conduit 105. Some of the liquid nitrogen from expansion chamber 100 may be led via conduit 111 back to conduit 98 and hence back to the air rectifier as reflux.

Liquid oxygen is drawn off from the air rectifier via conduit 107 as an end product. Where the methane has to be reformed by an oxidation process, this oxygen is readily available for this purpose.

I claim:

1. A method of producing liquid nitrogen in the course of the regasification of liquid methane which comprises
  - (a) cooling gaseous nitrogen by indirect heat exchange with compressed liquid methane to produce compressed gaseous methane,
  - (b) compressing the cold gaseous nitrogen from step (a),
  - (c) condensing the cold compressed gaseous nitrogen from step (b) by indirect heat exchange with liquid methane to produce compressed liquid nitrogen and gaseous methane, and
  - (d) additionally heating the compressed gaseous methane from step (a) to further raise its temperature and expanding it to produce energy.
2. A method as claimed in claim 1 in which the energy produced on expanding the compressed gaseous methane is used to drive the compressors used in the process.
3. A method as claimed in claim 2 in which the inlet temperatures of the various compressors is not higher than about -200° F.
4. A method as claimed in claim 1 in which the gaseous nitrogen is cooled to -200° F. to -250° F. by indirect heat exchange with compressed liquid methane.
5. A method for producing liquid nitrogen in the course of the regasification of liquid methane in which gaseous nitrogen is supplied from an air rectification plant operating in conjunction with the liquid methane regasification plant, said method comprising
  - (a) cooling compressed gaseous nitrogen taken overhead from an air rectification column by indirect heat exchange with compressed liquid methane to produce compressed gaseous methane,
  - (b) further compressing the cold gaseous nitrogen from step (a),
  - (c) condensing the cold compressed gaseous nitrogen from step (b) by indirect heat exchange with liquid methane to produce compressed liquid nitrogen and gaseous methane,
  - (d) cooling the air stream to the air rectifier by indirect heat exchange with compressed liquid methane to produce compressed gaseous methane,
  - (e) heating the compressed gaseous methane from steps (a) and (d) and expanding it to produce energy,

- (f) further cooling the cold air from step (d) by heat exchange with cold nitrogen from the air rectifier and passing the further cooled air to the air rectifier from which gaseous nitrogen is taken off as an overhead stream,
- (g) reducing the pressure on the liquid nitrogen from step (c) to produce liquid nitrogen at a lower pressure and cold gaseous nitrogen, and
- (h) returning some of the liquid nitrogen from step (c) to the air rectifier as reflux.

6. A method as claimed in claim 5 in which the cold gaseous nitrogen from step (g) is mixed with the cold gaseous nitrogen coming overhead from the air rectifier.

7. A process as claimed in claim 6 in which the cold gaseous nitrogen from step (g) is circulated through the coils of a re-boiler in the air rectifier.

8. A method as claimed in claim 5 in which step (g) is carried out in stages in two or more expansion chambers.

9. A method as claimed in claim 5 in which cold oxygen from the air rectifier is also used to cool the air flowing to the rectifier.

10. A method as claimed in claim 5 in which liquid oxygen is also taken off as an end product.

11. A method as claimed in claim 5 in which some of the liquid nitrogen from step (g) is returned to the air rectifier as reflux.

12. A method of producing liquid nitrogen in the course of the regasification of liquid methane which comprises

- (a) cooling gaseous nitrogen by indirect heat exchange with compressed liquid methane to produce compressed gaseous methane,
- (b) compressing the cold gaseous nitrogen from step (a),

5

10

15

20

30

30

(c) condensing the cold compressed gaseous nitrogen from step (b) by indirect heat exchange with liquid methane to produce compressed liquid nitrogen and gaseous methane, heating the compressed gaseous methane from step (a) and expanding it to produce energy, and

(d) obtaining further energy by heating up the compressed gaseous methane by means of an external energy-producing cycle in which heat is supplied to the compressed gaseous methane from a working medium of higher boiling point by heat exchange in a condenser in which the working medium is liquefied and the working medium is then brought to a higher pressure, vaporised at the higher pressure, expanded in an engine to produce energy and then recycled to the condenser.

13. A method as claimed in claim 12 wherein the external energy-producing cycle is a propane cycle.
